INGOT MOLD AND INGOT

Emil Gathmann, Baltimore, Md., assignor to
Gathmann Research Incorporated, Catons-
ville, Md., a corporation of Maryland

Application May 23, 1936, Serial No. 81,496

14 Claims. (Cl. 22—139)

This invention relates to ingot molds and ingots, and more particularly to molds and ingots of the general class in which the cross section is corrugated, or comprises inwardly curved and outwardly curved portions.

As is now known in the art, molds having such cross sectional contours possess certain desirable characteristics, one of which is their advantageous effect upon the chilling and cooling of the ingot. It has been found that the inwardly extending convex mold wall portions, by projecting inwardly towards the center of the ingot and into the mass of ingot metal, serve to chill the metal quickly, thus resulting in improved crystalline structure of the ingot metal and greater strength in the outer portion or zone of the ingot.

I have found that, in order to obtain the most beneficial results, the inwardly extending convex mold wall portions should constitute as large a part of the entire wall surface as possible without departing substantially from the smoothly corrugated contour. Thus the contour preferably should include inwardly extending convex wall portions constituting by far the greater part of the total wall surface, yet the outwardly extending concave wall portions should be rounded and struck from radii long enough to prevent the formation of too sharp ribs or protuberances on the ingot. I have found it advantageous to make the outwardly extending concave wall portions on as small radii as is commensurate with a smoothly corrugated contour. A further important consideration is that of so balancing and apportioning the radii of the convex and the concave wall portions as to provide a contour in which the taper longitudinally from top to bottom of the mold and ingot will be substantially uniform throughout the perimeter and the vertical length of the mold. Contours in accordance with the present invention are particularly advantageous in molds and ingots in which there is a considerable amount of longitudinal taper.

Accordingly an object of the invention is to provide an ingot mold of corrugated contour in which the inwardly extending convex wall portions constitute by far the greater part of the total wall area and in which the taper from top to bottom is substantially uniform throughout the perimeter and the vertical length of the mold.

A further object is to provide an ingot mold of the kind referred to in which the outwardly extending concave wall surfaces are struck by radii as short as is possible without departing from the smoothly corrugated contour.

A further object is to provide an ingot having

a contour corresponding to the mold contour referred to above. Other objects will be apparent from a reading of the following description, the appended claims, and the accompanying drawings, in which:

Figure 1 is a top plan view of one form of mold embodying the invention;

Figure 2 is a central vertical sectional view of the mold shown in Figure 1;

Figure 3 is a diagrammatic view in the nature of a section on the line 3—3 of Figure 1 and illustrating specific curvatures;

Figure 4 is a horizontal sectional view of an ingot of the kind produced by casting in a mold as shown in Figures 1 and 2;

Figure 5 is a part plan view of a modified form of mold embodying the invention;

Figure 6 is a part sectional view of an ingot of the kind produced by casting in a mold such as is shown in Figure 5;

Figure 7 is a part plan view of a further modified form of mold embodying the invention; and

Figure 8 is a part sectional view of an ingot of the kind produced by casting in a mold such as that shown in Figure 7.

The invention may be embodied in molds and ingots of various kinds, such as big-end-up and big-end-down. It will be understood, however, that the invention is not limited to molds and ingots having the specific contours disclosed herein by way of illustrating the invention in its now preferred forms.

Figures 1, 2, and 3 show a big-end-up mold A having a generally round or circular corrugated chamber contour. The mold is open at the top and is necked in at the bottom as shown at 1, the necked-in portion being provided with a tapered bottom opening 2. Preferably the longitudinal taper from the necked-in portion upwardly is uniform with the exception of the extreme upper part of the chamber. These features, as described so far, are old in the art and per se do not constitute the invention claimed herein.

In accordance with the present invention, a mold having a generally round cross sectional corrugated contour comprises matrix wall means including a plurality of alternately arranged convex portions which extend inwardly towards the center of the mold chamber, and concave portions which extend outwardly away from the center of the mold chamber. The concave portions are struck by radii which gradually increase in length from one end of the mold to the other and the lines of centers of these radii are inclined with respect to the longitudinal center line of the mold.

the radii of the concave portions being quite small at the bottom and smoothly increasing towards the top due to a uniform inclination of the center line 6 from the bottom to the top of the mold, this inclination being plainly shown by the relative dimensions 6^a and 6^b in Figure 3 of the drawings. As shown in Figures 1, 2, and 3, the mold chamber is defined by alternately arranged convex wall portions 3 and concave wall portions 4. In order that the chamber will have the desired longitudinal taper, the lines of centers 5 of the radii R of the convex wall portions 3 and the lines of centers 6 of the radii R' of the concave wall portions are inclined with respect 10 to the longitudinal axis or center line 1 of the mold. In this embodiment of the invention the radii R are of equal length from bottom to top of the mold, and, in a mold of about nineteen to twenty inches in mean diameter and about sixty 15 inches in height, the radii R preferably may be between three and one-half and four inches in length.

The radii R' of the concave wall portions 4 gradually increase in length from bottom to top 20 of the mold and the lines of centers 6 of the radii R' are inclined with respect to the axis or longitudinal center line 7 of the mold. In a mold of the size referred to the radii R' may vary from about three-eighths inch at the bottom of the 25 chamber to about one and one-eighth inches at the top. The radii R' at the larger end of the mold should not exceed approximately one-fifteenth of the maximum cross section of the mold chamber. The increase in the lengths of the 30 radii contributes to a longitudinal taper but it is not advisable to use radii varying too much, and in order to obtain the desired amount of taper the lines of centers 6 are inclined as shown by the relative dimensions 6' and 6" in Figure 3. 35 It will be observed that the outwardly extending concave wall portions 4 constitute sections of the surfaces of cones whose axes 6 are inclined with respect to the axis 1 of the mold and also with the molds of the mold chamber R'. This relative arrangement and apportioning of the lengths of the radii of the curved wall portions results in a contour having desired characteristics including: the inwardly extending convex portions constituting by far the greater part of the total wall 40 50 surface and at the same time maintaining the smoothly corrugated general contour; and the longitudinal taper being substantially the same throughout the perimeter.

The ingot I shown in Figure 4 has the same 55 general cross sectional contour as the mold shown in Figures 1, 2, and 3, so that no detailed description of the ingot is necessary. Briefly, however, the ingot contour comprises alternately arranged inwardly extending concave surface portions 3' and outwardly extending convex surface portions 4'. Each concave surface portion 3' is of uniform 60 radius from top to bottom and the line of centers of the radii is inclined with respect to the axis of the ingot. The radii of each convex surface 65 70 75 portions 4' vary from top to bottom and the line of centers of the radii of each surface portion 4' is inclined with respect to the axis of the ingot as well as to the surface of the outwardly-projecting salients. The radii of the convex surfaces 4' at the larger end of the ingot should not exceed approximately one-fifteenth of the maximum cross section of the ingot.

When the mold is small it is preferable for the radii of the inwardly curved convex wall portions 75 to vary from top to bottom of the mold. A mold

N of this kind having a mean diameter of about three and one-half inches and a height of about sixteen inches is shown in Figure 5. The radii S of the inwardly extending convex wall portions 8 vary from top to bottom. In the mold shown the radii S vary from two and three-eighths inches at the bottom to one and five-eighths inches at the top. The radii S' of the outwardly extending concave wall portions 9 vary in length from bottom to top of the mold and the line of centers of the radii of each wall portion 9 is inclined with respect to the axis as also with the wall of the mold.

The ingot J shown in Figure 6 has the same general cross sectional contour as the mold shown in Figure 5. The ingot comprises alternately arranged inwardly-extending concave surface portions 8' and outwardly extending convex surface portions 9'. Each concave surface portion 8' is struck from radii which gradually decrease from bottom to top of the mold, and each convex surface portion 9' is struck from radii which gradually increase in length from bottom to top of the mold, the line of centers for the radii of each convex portion 9' being inclined inwardly 25 with respect to the surface of the ingot.

Figure 7 illustrates the invention as embodied in a rectangular mold O of corrugated contour. This mold comprises four inwardly extending convex side wall portions 10, each of which is flanked by outwardly extending concave portions 11 which are connected to adjacent primary corner walls 12 by means of inwardly curved secondary corner walls 13. The primary side walls 10, the primary corner walls 12, and the secondary corner walls 13 all are struck from radii which vary in length from bottom to top of the mold, the line of centers of the radii of each of these wall portions preferably being parallel to the axis of the mold. However, in accordance with the present invention, the outwardly extending concave wall portions 11 are struck from radii T of varying lengths, and the line of centers of the radii of each of the wall portions 11 are inclined with respect both to the mold axis and the surface of the associated wall portion. In this respect the wall portions 11 are similar to the wall portions 4 of the mold shown in Figures 1, 3, and 5, see particularly the diagrammatic showing in Figure 3.

The ingot K shown in Figure 8 has a contour corresponding generally to that of the mold shown in Figure 7. The ingot contour includes four inwardly extending concave side surface portions 10' each of which is flanked by outwardly extending convex surface portions 11' which are connected to adjacent primary corner surfaces 12' by means of inwardly curved secondary corner surface portions 13'. The radii of the primary side surfaces 10', the primary corners 12', and the secondary corner surfaces 13' vary in length from bottom to top of the ingot, and the lines of centers of these radii preferably are parallel to the axis of the ingot. The radii of the outwardly curved surface portions 11' vary in length 6 from bottom to top of the ingot, and the lines of centers of these radii are inclined with respect to both the axis and surface of the ingot.

By using contours of the kind described above it is possible to have the outwardly extending 7 concave mold wall portions struck on as small radii as is compatible with the maintaining of a smoothly corrugated contour, and smaller than has heretofore been possible with radii of uniform length or with radii struck from centers 7

parallel with the axes of the mold and ingot. This causes the inwardly extending convex mold wall portions to constitute by far the greater part of the total wall surface, and moreover, the longitudinal taper, although not mathematically uniform, is substantially uniform throughout the vertical length and perimeter of the mold. Structures having contours in accordance with my invention lead to more nearly uniform cooling and solidification of the outer crystalline structure of the ingot from the bottom to the top. The contour of the ingot surface is such that there is little danger of dendritic cleavage planes, which are sometimes subcutaneous and sometimes appear as open cracks at the convex portions of the ingot when the radii are struck from centers on a line parallel either with the longitudinal center of the ingot or with the surface of the ingot.

Furthermore, because of the more uniform solidification of the skin of the ingot, the interior structure of the ingot has been found to be sounder and of greater homogeneity.

The specific contour of any mold may have to be varied in dependence upon such factors as mold size, ingot metal analysis, and melting and pouring practice, so that various changes may be made in the contours disclosed herein for illustrative purposes without departing from the invention as defined in the claims.

I claim:

1. A longitudinally tapered ingot mold having inwardly extending convex wall portions and outwardly extending concave wall portions, said concave wall portions comprising surfaces of cones having their axes inclined with respect to the longitudinal center line of the mold chamber, said axes sloping away from said center line from the smaller end of the mold to the larger end thereof.

2. A longitudinally tapered ingot mold having inwardly extending convex wall portions and outwardly extending concave wall portions, at least some of said portions being generated by radii which gradually increase in length from the smaller end of the mold to the larger end thereof and the lines of centers of which are inclined with respect to the longitudinal center line of the mold chamber, said lines of centers sloping away from the center line of the mold from the smaller end of the mold to the larger end thereof.

3. A longitudinally tapered ingot mold having inwardly extending convex wall portions and outwardly extending concave wall portions, at least some of said concave portions being generated by radii which gradually increase in length from the smaller end of the mold to the larger end thereof and the lines of centers of which are inclined with respect to the longitudinal center line of the mold chamber, said lines of centers sloping away from the center line of the mold from the smaller end of the mold to the larger end thereof.

4. A longitudinally tapered ingot mold having inwardly extending convex wall portions and outwardly extending concave wall portions, at least some of said convex portions being generated by radii which gradually increase in length from the smaller end of the mold to the larger end thereof and the lines of centers of which are inclined with respect to the longitudinal center line of the mold chamber, said lines of centers sloping away from the center line of the mold from the smaller end of the mold to the larger end thereof.

5. A longitudinally tapered ingot mold having a mold chamber defined by wall means comprising a plurality of inwardly extending convex wall portions and outwardly extending concave wall portions, certain of said wall portions each comprising a part of the surface of a cone whose axis is inclined with respect to the longitudinal center line of the mold, said axes sloping away from said centerline from the smaller end of the mold to the larger end thereof.

6. A longitudinally tapered ingot mold having inwardly extending convex wall portions and outwardly extending concave wall portions, said convex wall portions comprising surfaces of cones having their axes inclined with respect to the longitudinal center line of the mold chamber, said axes sloping away from said center line from the smaller end of the mold to the larger end thereof.

7. An ingot mold as defined in claim 2 in which the mold walls taper outwardly from bottom to top.

8. A longitudinally tapered ingot having outwardly-extending convex surface portions and inwardly extending concave surface portions, at least some of said portions being generated by radii which gradually increase in length from the smaller end of the ingot to the larger end thereof and the lines of centers of which are inclined with respect to the longitudinal center line of the ingot, said lines of centers sloping away from the center line of the ingot from the smaller end of the ingot to the larger end thereof.

9. A longitudinally tapered ingot mold comprising four side walls and four corner walls defining a chamber generally rectangular in cross section, at least two opposed side walls each comprising a centrally disposed primary side wall portion, two outwardly extending concave wall portions flanking and merging with the primary side wall portion, and two secondary corner wall portions flanking and merging with said concave wall portions and connecting the latter to the adjacent corner walls, said concave wall portions being generated by radii which gradually increase in length from the smaller end of the mold to the larger end thereof and the lines of centers of which are inclined with respect to the longitudinal center line of the mold chamber, said lines of centers sloping away from the center line of the mold from the smaller end of the mold to the larger end thereof.

10. A longitudinally tapered ingot generally rectangular in cross section and comprising four side surfaces and four corner surfaces, at least two opposed side surfaces each comprising a centrally disposed primary side surface portion, two outwardly extending convex surface portions flanking and merging with said primary side surface portion, and two secondary corner surface portions flanking and merging with said convex wall portions and connecting the latter to the adjacent corner surfaces, said convex surface portions being generated by radii which gradually increase in length from the smaller end of the ingot to the larger end thereof and the lines of centers of said radii being inclined with respect to the longitudinal center line of the ingot, said lines of centers sloping away from the center line of the ingot from the smaller end of the ingot to the larger end thereof.

11. A tapered ingot mold having inwardly-extending convex wall portions and outwardly-extending concave wall portions, at least some of said concave portions being generated by radii

which gradually increase in length from one end of the mold to the other and the lines of centers of which are inclined with respect to the longitudinal center of the mold chamber, said lines of centers sloping away from the center line of the mold from the smaller end of the mold to the larger end thereof, said radii at the larger end of the mold not exceeding approximately one-fifteenth of the maximum cross section of said mold chamber.

12. A tapered ingot having outwardly-extending convex surface portions and inwardly-extending concave surface portions, at least some of said convex portions being generated by radii which gradually increase in length from one end of the ingot to the other and the lines of centers of which are inclined with respect to the longitudinal center line of the ingot, said lines of centers sloping away from the center line of the ingot from the smaller end of the ingot to the larger end thereof, said radii at the larger end of the ingot not exceeding approximately one-fifteenth of the maximum cross section of said ingot.

13. A longitudinally tapered ingot mold comprising side walls and concave corner walls defining its chamber, said corner walls being generated by radii which gradually increase in length from the smaller end of the mold to the larger end thereof and the lines of centers of which are inclined with respect to the longitudinal center line of the mold chamber, said lines of centers sloping away from the center line of the mold from the smaller end of the mold to the larger end thereof.

14. A longitudinally tapered ingot comprising side surfaces and convex corner surfaces, said corner surfaces being generated by radii which gradually increase in length from the smaller end of the ingot body to the larger end thereof and the lines of centers of which are inclined with respect to the longitudinal center line of the ingot, said lines of centers sloping away from the center line of the ingot from the smaller end of the ingot body to the larger end thereof.

EMIL GATHMANN.
